United States Patent Office

Des. 207,079
Patented Feb. 28, 1967

207,079

SURGICAL PILLOW

Lillian B. Wirth, 220 Seavy Road,
Corvallis, Oreg. 97113

Filed Mar. 25, 1966, Ser. No. 1,686

Term of patent 7 years

(Cl. D83—1)

FIG. 2.

FIG. 3.

FIG. 1.

FIG. 4.

FIG. 1 is a top plan view of a surgical pillow showing my new design;

FIG. 2 is an elevation showing the thicker back end of the pillow;

FIG. 3 is a side elevation showing the longitudinal taper of the pillow from the thicker back end to the thinner front end; and

FIG. 4 is an elevation showing the thinner front end of the pillow.

The underside of the pillow is substantially the same as the top plan view of FIG. 1.

I claim:

The ornamental design for a surgical pillow, as shown and described.
